RIVET PUNCH

Filed May 5, 1924

Patented June 22, 1926.

1,589,645

UNITED STATES PATENT OFFICE.

WILLIAM J. HEYL, OF CLAIRTON, PENNSYLVANIA.

RIVET PUNCH.

Application filed May 5, 1924. Serial No. 711,186.

My invention consists of an improved machine for the purpose of punching and inserting rivets in the ends of connecting metallic strips, for rivet connection with sheet metal or other members in building construction and similar operations.

Ordinarily, the strips of thin sheet metal are cut to length, and rivets are punched thereto by driving them through the metal by a hammer over a nut or other hollow bearing, ready for application and attachment by riveting to the structural member, in the manner commonly employed.

The present invention is generally similar to that of my prior application filed March 31, 1923, Serial No. 703,188. It has in view to provide means for the same general purpose, utilizing a lever actuated punching plunger and bending plate, operable upwardly from below toward a relatively stationary co-acting die adapted to receive the end of the blank, together with means for automatically feeding the rivets by gravity in a continuous row, and various other features of construction and operation as hereinafter described.

Referring to the drawings:

Fig. 1 is a face view of the machine in front elevation, partly broken away, showing the plunger partly raised;

Fig. 2 is a vertical sectional view on the line II—II of Fig. 1;

Fig. 3 is a partial similar view, showing the punching die and plate in elevated position;

Fig. 4 is a sectional plan view, enlarged, on the line IV—IV of Fig. 1;

Fig. 5 and Fig. 6 are sectional detail views showing the vertically acting plunger in lowered and partly raised positions respectively, and in operative relation to the next succeeding rivet;

Fig. 7 is a horizontal sectional detail view on the line VII—VII of Fig. 6;

Fig. 8 is a cross section, enlarged, through the rivet chute, on the line VIII—VIII of Fig. 1;

Fig. 9 is a plan view of the receiving end of the rivet chute;

Fig. 10 is a sectional detail view, partly on the line X—X of Fig. 4, showing the plunger lowered.

The supporting frame of the machine consists of a base 2 which may conveniently be in cast form adapted for fastening against a foundation or supporting base of

timber, etc., by nails or screws through openings 3. Blocks 4 and 5 respectively are secured to the base 2 by bolts 6, or may be integral therewith, as desired, and provide an upper punching die and a lower plunger and plate bearing, respectively, in vertical alinement, for operation upon the end of the blank b. The punch bar or plunger 7, which is preferably cylindrical, is reciprocably mounted in a cylinder bearing 8 of block 5, in central alinement with the punching hole 10 of block 4, which hole extends through the bottom thereof and into the upper enlarged cavity 11. Said cavity provides for clearance of the cuttings, the front bottom portion of the opening being inclined downwardly beyond punching hole 10, as indicated at 12 for discharge of the waste cuttings.

For the purpose of actuating plunger 7, I provide an operating lever 9, pivotally mounted on base 2 by bolt 13, having an outer handle terminal 14 and an inner comparatively short lever portion 15. The upper portion of lever extension 15 is preferably rounded, as at 16, bears against the lower end of plunger 7, as in Fig. 2, and is adapted to impart to the plunger sufficient upward movement when the lever is operated to effect upward punching movement of the rivet a, through the end of blank b, and through punch hole 10, as in Fig. 3.

For the purpose of providing a front bending element against which the blank b may be bent downwardly at the desired angle, as indicated in dotted lines, Fig. 3, I provide a slidably movable plate 17 mounted in the recessed central face of block 5, between the inner edges 18—18 thereof and partly covered or enclosed by the heads of bolts 6. The upper terminal edge of plate 17 is slightly tapered as at 19, providing a narrow blunt bending edge for the blank. The lower edge of the plate tapers inwardly and terminates in a bearing terminal 20, which rests upon a lug or abutment 21 secured to the face of lever terminal 15 in any suitable way, as by a holding bolt 22. The upper face of abutment 21 is tapered, as shown in Fig. 1, so that, when the plunger and plate are elevated, bringing the plunger and rivet to the limit of their upward movement with the rivet inserted in the clip, the plate will rest flatly against the upper surface of the abutment, and its edge is in proper bearing engagement

against the clip for bending. When lowered, the plate rests against the upper corner portion of the abutment, but when raised, it bears across the flat tapered face, and thus 5 is solidly supported under the strain of bending. Abutment 21 may, however, be of any other suitable form adapted to provide a good solid bearing for the plate.

For the purpose of automatically feeding the rivets *a* one by one successively to operative position over the upper end of plunger 7, I provide an inclined chute 23 having a curved steep portion *c* and a somewhat flatter portion *d* extending outwardly 10 to any desired extent and terminating in a flared insertion opening 24. The chute as thus made consists of the base portion 23 having the central longitudinal recess 25 adapted to receive the heads of the inverted 15 rivets and supplemental side plates 26—26 secured thereon by screws or the like, and providing the narrow central opening 27 for clearance of the upwardly extending shanks of the rivets.

20 The outer section *d* and inner section *c* merge into each other and are connected together by and supported upon a bracket 28 of the base 2, as in Fig. 1. The lower portion of the rivet chute, as thus made, curves 25 inwardly and terminates substantially on a level with the upper terminal of plunger 7, as in Fig. 10, when the lever terminal 15 is lowered.

25 The portion *d* of the chute constitutes a feeding reservoir, of any desired length, and with sufficient gravitating slope to insure a constant supply of closely adjacent rivets to the upper end of the steeper portion *c*.

30 Such portion *c* constitutes an easily sliding feeding extension of section *d* to ensure a positive supply of rivets to operative position over the plunger, one by one. For such purpose, its inclination is considerably 35 steeper than section *d* at the upper portion, gradually flattening towards the delivery terminal, where the endmost rivet is positively forced by the rear rivets outwardly 40 from between the strips 26 and on to the top of plunger 7.

45 For the purpose of ensuring centering of the rivet over the plunger 7, the opposite wall portion of block 5 is rounded, as at 29, providing a substantially semi-cylindrical wall against which the edge of rivet *a* will bear, as pushed downwardly and outwardly by the continuous gravitating row 50 of rivets in the chute. Curved wall 29 is preferably of a radius slightly greater than that of the rivet head, and the inner edges of central recessed channel 25 align with the outside edges of such semi-circular portion, ensuring the centralizing location of 55 the rivet over the plunger and in alinement 60 with the punch hole 10.

Plunger 7 is maintained in its vertically reciprocal position and against turning by a guiding key or spline 30 of stud 31 inserted through the back of block 5. Plunger 7 has a corresponding keyway 32 engaging 70 the key or spline 30 and of proper length to allow for the desired movement, with limiting engagement against the key on downward travel. By this means, the plunger may fall until its upper end is 75 level with the bottom of the chute, for smooth movement of the rivet.

The plunger is of about the same diameter as that of the rivet head and is provided at its upper corner portion with a slight bevel terminal 33, facing the advancing rivets. The purpose of such bevel is to allow for wedging back the next oncoming rivet *a* on upward movement of the plunger, to avoid interference, wherever there is variation in the diameter of the rivet heads allowing slight overlap, while always ensuring the positive location of the rivet to be operated upon over the top of the plunger 90 and in central alinement with the punching hole 10. Said hole is slightly larger than the shank of the rivet, providing for ample clearance and any slight variation from exact central alinement.

95 By such construction, the feed chute may be kept full or partly full of rivets, introduced at its outer end, the weight of which will positively feed the lower rivets downwardly and inwardly, one at a time, over the operating plunger. The upper block 100 4 is provided with an insertion recess 34 immediately underneath the punch hole and between the lateral shoulders 35—35 and the block, between which the strip *b* may be inserted endwise against the front limiting face of block 2, as in Fig. 3. Thereupon, lever 9 is actuated, thrusting the plunger 7 upwardly, forcing the rivet through the blank, the rivet itself acting as the punch, the cutting passing outwardly through enlarged opening 11. While in such position, with bending edge 19 of plate 17 immediately underneath the blank, the blank *b* may be bent downwardly over edge 19 at any desired angle, whereupon the lever is retracted 110 and the blank withdrawn, and its other end inserted for a similar operation, as will be 115 readily understood.

120 At each operation, an additional rivet is automatically placed in position over the plunger, as long as sufficient rivets are maintained in the guiding chute, so that at each manipulation of the lever, one complete 125 operation is performed.

130 It will be understood, of course, that any suitable mechanical actuating mechanism may be connected with lever 9, in place of hand operation, without otherwise affecting the operation. Also, that lever 9 may be located at the left side of the machine, if

preferred, for which purpose, an additional bolt hole 36 is provided, for pivotal mounting by bolt 13.

The construction and operation of the invention will be readily understood and appreciated from the foregoing description. The device is extremely simple, cheap and efficient, and is capable of rapid and continuous use. It may be modified or changed in detail construction by the skilled mechanician, but all such changes are to be understood as within the scope of the following claims.

I claim:

1. A punching and rivet inserting machine consisting of an upper stationary punching die, a lower reciprocable plunger, a guiding housing therefor having a rivet centralizing abutment, means for delivering a rivet to operative position on the top of the plunger and against said abutment, a vertically movable bending plate in front of the punching die, and means for actuating the plunger and bending plate together.

2. In combination with a supporting base, a plunger bearing block having a horizontal rivet receiving opening and an oppositely arranged upwardly extending concaved bearing face, a reciprocable plunger provided with a beveled corner, a guiding key for the plunger, a co-acting vertically movable bending plate in front of said plunger, a laterally arranged inclined rivet feeding chute consisting of an outer inclined portion, an abruptly steep middle portion and a short horizontal delivery portion leading to the receiving portion of the bearing block adapted to deliver rivets by gravity point upwardly against the block and over the plunger, an actuating plunger lever, and an upper die block having a registering punch hole for the rivet.

3. In combination with a supporting base, a plunger bearing block having a concaved abutment and a reciprocable plunger provided with a beveled corner, a guiding key for the plunger, a laterally arranged inclined rivet feeding chute adapted to deliver rivets by gravity point upwardly against the concaved abutment of the block and over the plunger, a reciprocable bending plate slidably mounted on the block, an actuating lever for simultaneously lifting the plunger and said plate, and an upper stationary die block on the base having a registering punch hole for the rivet and a blank receiving socket for insertion of a blank between the punch hole above and the plunger and bending plate below.

4. In combination with a supporting base having a fixedly mounted upper stationary punching die provided with a lower blank receiving recess, a lower plunger bearing block secured to the base having a half round bearing extension providing a limit-

ing abutment, a reciprocable plunger in said bearing, an inclined rivet feeding chute leading into the plunger block opposite to said abutment, a reciprocable bending plate slidably mounted on the front of the plunger bearing block, and an operating lever for the plunger having a portion engaging the bending plate for imparting simultaneous upward movement to the plunger and bending plate.

5. In combination with a supporting base having a fixedly mounted upper stationary punching die provided with a lower blank receiving recess, a lower plunger bearing block secured to the base having a half round bearing extension providing a limiting abutment, a reciprocable plunger in said bearing, an inclined rivet feeding chute leading into the plunger block opposite to said abutment, a reciprocable bending plate slidably mounted on the front of the plunger bearing block, and an operating lever for the plunger having a beveled abutment engaging the lower end of the bending plate for imparting upward movement to it simultaneously with upward movement of the plunger.

6. In combination with a supporting base having a fixedly mounted upper stationary punching die provided with a lower blank receiving recess, a lower plunger bearing block secured to the base having a half round bearing extension providing a limiting abutment, a reciprocable plunger in said bearing, an inclined rivet feeding chute leading into the plunger block opposite to said abutment, a reciprocable bending plate slidably mounted on the front of the plunger bearing block, and an operating lever for the plunger having a partly rounded terminal in registering engagement with its lower end and a laterally arranged abutment in register with the bending plate having a sloping face adapted to bear against the lower end of the bending plate when raised, whereby to support the bending plate in position with its lower edge underneath the blank at the time the plunger has forced a rivet through the blank while it is pressed upwardly against the die.

7. In combination with a supporting base having an upper fixedly attached punching die, a bearing block on the base having a vertical plunger bearing cavity, a lateral rivet feeding chute at one side of the bearing cavity, a rounded limiting abutment forming an arresting terminal at the opposite side thereof, and a reciprocable plunger therein provided with a guiding and limiting keyway and key and having a beveled corner facing the feeding chute.

In testimony whereof I hereunto affix my signature.

WILLIAM J. HEYL.
